UNITED STATES PATENT OFFICE.

FREDERICK SCHMID AND MORRIS ROSOW, OF PHILADELPHIA, PENNSYLVANIA.

CONTAINER DEVICE.

Application filed March 15, 1921. Serial No. 452,560.

To all whom it may concern:

Be it known that we, FREDERICK SCHMID and MORRIS Rosow, citizens of the United States, residing at Philadelphia, county of Philadelphia, and State of Pennsylvania, have invented certain new and useful Improvements in Container Devices, of which the following is a specification.

One object of our invention is to provide an improved food container which can be attached to the outer side of a building adjacent a window and which can be easily swung from a position directly in front of the window into a position in front of the adjacent wall; said container having an opening which, when the device is in front of the window, will allow access to the interior of the container and when the device is swung in front of the wall, the latter will form a closure for said opening.

Another object is to provide means of simple construction which will facilitate the swinging action and at the same time will hold and prevent the container from accidentally swinging away from in front of the wall.

A further object is to make the device of our invention of a strong and durable construction which can be easily and cheaply manufactured.

These objects, and other advantageous ends which will be described hereinafter, we attain in the following manner, reference being had to the accompanying drawings in which—

Figure 1 is an elevation showing a building having a side wall with a window, the device of our invention being attached and illustrated in a position in front of the wall with the wall forming a closure for the opening of the container.

Figure 2 is a sectional plan view taken on the line 2—2 of Figure 1.

Figure 3 is a view looking in the direction of the arrow *x* in Figure 1; the wall being shown in section.

Figure 4 is a view of similar character to Figure 2 showing the container swung in midway position from the wall to the window or vice versa.

Figure 5 is a front elevation showing the container having been swung in front of the window with the sash of the window raised to permit access to the interior of the container for the purpose of putting

food therein or removing food therefrom; said view being shown on an enlarged scale,

Figure 6 is a view looking from the inside of the window and showing the container in the position illustrated in Figure 5 and drawn on the same scale as Figures 1 to 4 inclusive, and

Figure 7 is an enlarged fragmentary sectional plan view taken on the line 7—7 of Figure 1.

Referring to the drawings, 8 represents a building having a wall 9 in which is positioned a window 10 having a sash 11 which can be raised and lowered in the usual manner. Our improved device includes a box 12 which is preferably made rectangular with a straight front providing an opening 13. A frame 14 includes two main supporting strips 15 which are preferably joined by reinforcing brace bars 16 as clearly shown in Figures 1 and 5. This frame is secured by screws or other suitable means to the outer closed side 17 of the box 12 opposite and parallel with the opening 13. The main supporting strips 15 have two pairs of upright bearings 18 and 19 secured thereto with their axes parallel; the bearings of the pair 18 being positioned one directly above the other as are also the bearings of the pair 19.

A yoked pivotal supporting brace 20 has integral parallel arms 21 and 22 and an upright connecting rod portion 23 which fits within the bearings 18 between the arms 21 and 22 as clearly shown in Figures 1 and 5. The arms 21 and 22 of the yoke 20 have vertically extending hooked ends 24 and 25 which respectively fit in vertical holes in wall brackets 26 and 27; said holes being positioned one directly above the other and so that the brackets form socket bearings to permit the yoke 20 to swing thereon as an axis with the arms 21 and 22 movable in horizontal planes and so that the rod portion 23 of the yoke maintains a vertical position and moves concentric to the coincident axes of said holes in the brackets 26 and 27.

An auxiliary support 28 includes a vertical rod 29 which extends through the bearings 19 and an integral arm 30 at its lower end below the bottom bearing 19; said arm 30 being arranged horizontally and having a vertically hooked depending end 31 which fits in a hole in the bracket 27 parallel with the hole in which the end 25 of the arm 22

fits. The holes in the brackets 26 and 27 are arranged parallel with the bearings 18 and 19 and the arm 30 is arranged parallel with the arm 22 of the yoke 20. The arms 5 21, 22 and 30 are of greater length than the distance between the closed side 17 of the box and the front part of the opening 13 and when the box is either entirely in front of the wall 9 or window 10, the arms will be 10 positioned at a slant as shown for example in Figures 2 and 7. The brackets 26 and 27 can be secured in any suitable manner to the window frame and it will be noted that when the box is swung for example from the position shown in Figures 5 and 6 in 15 front of the window, the front of the box will move so as always to be parallel with the wall and window as clearly shown in Figure 4 so that when the box is moved into the position shown in Figures 1 and 2, the 20 edge of the box providing the opening 13 will abut the wall and be parallel therewith so that the wall will form a closure for the opening as shown in Figure 7. When, however, the box is swung into a position in 25 front of the window as shown in Figures 5 and 6, access may be had to the interior of the box through the opening 13 by raising the sash 11 so that any articles of food can be 30 inserted or removed as clearly obvious from Figure 6 of the drawing.

In order to lock the box, we provide a bolt 32 which is in the form of a plate having an upright slot 33 through which headed pins 34 extend into the end 35 of the box 12. The upper end of the plate 32 has a handle portion 36 so that by grasping the handle portion the box can be swung into any of said positions and the bolt can be raised and 40 lowered. The bolt 32 is so arranged as shown in Figure 7 that when lowered while the box is in position directly in front of the wall, said bolt will enter the space between the arms 22 and 30 and will abut the 45 inner surface of said arm 30; thus preventing the box from moving away from the wall since with the construction as illustrated and above described the box must necessarily move in a parallel path and when the bolt 50 is in its lowered position it will jam against the arm 30 if it is attempted to swing the box away from the wall. However, when the bolt is raised so that its lower end clears the top of the arm 30, the box may be swung 55 into any of said positions.

While we have described our invention as taking a particular form, it will be understood that the various parts of our invention may be changed without departing from the 60 spirit thereof, and hence we do not limit ourselves to the precise construction set forth, but consider that we are at liberty to make such changes and alterations as fairly

come within the scope of the appended claims.

Having thus described our invention, what we claim as new and desire to secure by Letters Patent is:—

1. The combination with a building, having a wall and a window in the wall, of a box having an opening, a pivotal mounting for the box whereby it may be swung to face the window or to face the wall, and a pivoted arm adapted to hold the box in the same horizontal plane, substantially as described. 75

2. The combination with a building, having a wall and a window in the wall, of a box having an opening, a support pivotally connected with the wall and the box, an auxiliary support, pivotally connected with the wall and the box and parallel with the first named support, whereby the box will be maintained in the same horizontal plane and may be swung to face the window or to face the wall, substantially as described. 85

3. The combination with a building having a wall and a window in line with said wall, of a device including a box having an opening; a support pivotally connected to said building and including an arm pivotally connecting and supporting said box; an auxiliary support having a portion pivotally connected to said box and an arm leading from said portion and pivotally connected to said building whereby the box may swing on said supports with its opening in registry with said window into a position directly in front of said wall; and a bolt on said box, adapted to be moved into a position between said arms, whereby the pivotal movement of said box is prevented; substantially as described. 95

4. The combination with a building having a wall and a window in line with said wall, of a device including a box having an opening; a bearing on said box; a yoked supporting member having an upright rod portion and arms leading from said portion and pivotally supported on said building; and an auxiliary support pivotally connected to said box and having an arm extending substantially parallel to said first arms, said auxiliary arm also being pivotally connected to said building whereby the box may be swung from a position parallel with the wall with its opening opposed thereto into a position in which the opening will register with said window; substantially as described. 110 115

In testimony whereof we have signed our names to this specification in the presence of 120 two subscribing witnesses.

FREDERICK SCHMID,
MORRIS ROSOW.
